UNITED STATES PATENT OFFICE.

ALFRED COCHRAN, OF BROOKLYN, NEW YORK, ASSIGNOR OF ONE-HALF TO THOMAS COCHRAN, OF NEW YORK, N. Y.

PROCESS AND APPARATUS FOR CRACKING AND DISTILLING HYDROCARBONS.

1,296,367.

Specification of Letters Patent.

Patented Mar. 4, 1919.

Application filed April 8, 1916. Serial No. 89,827.

To all whom it may concern:

Be it known that I, ALFRED COCHRAN, a citizen of the United States, and a resident of the city of New York, borough of Brooklyn, in the county of Kings and State of New York, have invented a new and Improved Process and Apparatus for Cracking and Distilling Hydrocarbons, of which the following is a full, clear, and exact description.

The invention relates to the cracking and distilling of petroleum and other hydrocarbons for the production of gasoline, benzene, toluene and the like, and its object is to provide a new and improved process and apparatus for cracking and distilling hydrocarbons in a very simple and economical manner with less production of carbon, a higher yield, increased production and uniform nature of the resultant gases and vapors.

The method consists essentially in simultaneously subjecting the hydrocarbon to heat and to an attrition action. Use is also made of a revoluble heated retort containing loose heat-conducting mediums such as metallic balls in rubbing contact with each other and with the interior surface of the retort.

A practical embodiment of the invention is represented in the accompanying drawings forming a part of this specification, in which Figure 1 is a longitudinal central section of the apparatus for cracking and distilling hydrocarbons.

Fig. 2 is a fragmentary sectional view illustrating different varieties of catalytics.

In furnaces for cracking and distilling hydrocarbons as heretofore constructed, the hydrocarbons passing into the retort are subjected to a high heat next to the walls of the heated retort and to a considerably less degree of heat at the middle of the retort, and as the reacting gases and vapors have a very low heat conductivity it is evident that they are unevenly heated, and a large amount of coke, tar and fixed gases are formed with relatively low yields of valuable products. With the improved retort presently described in detail the above described difficulties are overcome, and the heat is taken from the rim of the retort and distributed uniformly throughout the volume of the reacting gases and vapors thus insuring a uniform heating of the gases

which with an attrition action produces the desired result.

A suitably constructed furnace 10 is provided with a burner 11 for exteriorly heating a revoluble cylindrical retort 12 mounted in the furnace 10. The retort 12 is provided at its ends with heads 13 and 14 to which are secured hollow trunnions 15 and 16 journaled in suitable bearings 17 and 18 attached to the ends of the furnace 10. The hollow trunnion 15 is provided with apertures 19 in register with a supply pipe 20 attached to the bearings 17 and this supply pipe 20 is connected with a suitable supply of the hydrocarbon to be cracked and distilled. A pipe 21 connected with a water or a steam supply connects with the pipe 20 near the outlet end thereof so that both hydrocarbon and water pass simultaneously into the trunnion 15 and from the same into one end of the retort 12 by way of apertures 22 formed in the head 13 at the opening of the trunnion 15. By this arrangement the incoming hydrocarbon and water are somewhat spread or distributed.

The other trunnion 16 is provided with apertures 23 connected with an outlet pipe 26 attached to the bearing 18 for conducting the resultant gases and vapors to a condenser for condensing the said gases and vapors. The head 14 is provided with apertures 27 opening into the trunnion 16 to allow the resultant gases and vapors to pass from this retort 12 into the trunnion 16 and from the latter to the outlet pipe 26. The outer end of the trunnion 16 is connected with other machinery for imparting a continuous rotary motion to the retort 12, and for this purpose use may be made of a sprocket wheel 30 secured on the trunnion 16 and connected by a sprocket chain with other machinery. It is expressly understood that I do not limit myself to any particular driving means for the retort 12.

The retort 12 contains heat-conducting mediums 40, preferably in the form of metallic balls, in rubbing contact with each other and with the interior surface of the retort 12. It is understood that when the retort 12 is rotated the balls 40 by their own weight are set in motion and rub against each other and against the interior surface of the retort 12. The retort 12 is provided with a suitable manhole 50 for placing the balls 40 within the retort or removing same

therefrom whenever it is desired to do so. The retort 12 is also provided with a drain cock 51 for draining the heavy residues from the retort 12 at the time the latter is 5 at a standstill and the drain cock 51 is in lowermost position.

The operation is as follows:

When the retort 12 is rotated and heated from the flame emanating from the burner 10 11 and the hydrocarbon passes into the retort by way of the pipe 20 and the trunnion 15 then such incoming hydrocarbon is subjected to heat and to a rubbing action by contact with the balls 40 and the interior 15 surface of the retort 12 whereby the hydrocarbon is quickly cracked and vaporized before reaching the trunnion 16 and the pipe 26 for carrying off the cracked gases and vapors. It will be noticed that by the arrangement described, the heat of the rim of the retort 12 is taken up by the metallic balls 20 40 and this heat is by conduction, convection and radiation passed to the hydrocarbon within the retort 12 thus practically reaching 25 every particle of the hydrocarbon passing into the retort 12 thereby insuring a high yield of gases and vapors of a relatively uniform nature. As the balls 40 extend throughout the length of the retort 12, it is evident that the heat is uniformly distributed 30 within the retort to produce the desired result. It will be noticed that by the continuous rubbing action of the balls 40, choking 35 of the retort by a rapid accumulation of carbon deposits is entirely prevented and the retort can be used for quite a length of time without requiring stopping thereof for the removal of possible carbon deposits and heavy residues, as is frequently the case 40 with apparatus as heretofore constructed.

The retort 12 may be filled completely with the balls 40 or, at least, slightly more than half full, as shown, so that the balls extend above the apertures 22 and 27. By this arrangement the hydrocarbon entering the retort is subjected to the heat emanating from the balls 40 and to the rubbing action thereof. The pressure under which the hydrocarbon enters the retort and the degree of heat 50 to which the latter is subjected depends on the nature of the hydrocarbon treated at the time and the products desired.

The apparatus is well adapted to catalytic operations through the medium of added 55 catalysts: for example, balls of nickel, cobalt or other substances may be used either with or without the addition of catalyzing metals, oxids and salts, and of water to promote desirable decomposition. The attrition 60 of the balls in rolling causes fresh surfaces to be constantly exposed to the reacting gases so that the catalytic effect is practically continuous.

In practice, the retort 12 and the balls 40 65 are preferably made of iron, and it is evi-

dent that by the use of such balls the heat of the retort rim is rapidly transferred to the interior of the retort thus promoting uniform heating of the reacting gases and vapors.

It will also be noticed that by the arrangement described, first a grinding action is had in the ball-filled revolving retort to pulverize the carbon and thereby prevent an undesirable obstruction in the retort, second an attrition action is produced to expose fresh surfaces for catalytic effect, and third the rapid transfer of heat from the rim of the retort to the interior thereof, as above explained.

In the cracking or decomposing of hydrocarbon oils for the manufacture of gasoline the iron balls are preferably of about one inch in diameter and use is made of a catalyst such as grain nickel with a temperature 85 in the interior of the retort of from 300° to 500° C. and a pressure of about ten atmospheres in the retort and condenser. For the manufacture of benzene, toluene and other aromatic hydrocarbons the same balls and 90 catalysts are used but the temperature is raised to from 500° to 650° C.

It is evident that I do not limit myself to the exact sizes of the balls, the pressure and the degrees mentioned as the same may 95 be varied without deviating from my invention.

The apparatus will serve many operations involving reactions, namely, between gases, between gases and liquids, between gases and 100 solids, and between liquids and solids, either with or without pressure, either with or without heat or either with or without catalysts.

I do not limit myself to the exclusive use 105 of metallic balls as the retort filling for the reason that a wide diversity of substances might be used of regular or irregular shape: for instance, fragments of pumice, of coke, shot nickel, oxids and salts, in crystal, grain 110 or powder form.

The apparatus may be used in connection with gases, vapors, oils, tars and greases for petroleum and coal distillations or with any other product, oily or otherwise, where distillation, decomposition or treatment with reagents may be indicated. As examples of such other processes I mention the hydrogenation of fatty oils in the presence of 120 catalysts; the production of oxalates by the reaction between carbon monoxid and alkalis; the production of sulfuric anhydrid by the reaction between sulfur dioxid and oxygen; and the distillation of coal for the production of fixed-gas, oils, tar, coke and other 125 products.

I may operate with and without water (or steam). Water (or steam) is usually desirable and amounting about equal to that of the oil under treatment, weight for weight,

when cracking and distilling heavy hydrocarbon oils for the production of gasoline, promoting the reaction at a comparatively low temperature (from 300° C. to 500° C.)

5 and lessening the formation of fixed gases. The water is introduced through the pipe 21 and mixes with the oil from the pipe 20, both oil and water being usually supplied from separate closed tanks, (not shown), 10 where each is under the same pressure (pressure produced by compressed air or other means) and after the reaction in the retort the resulting gases and vapors make their exit to a condenser (not shown) through the 15 pipe 26. For the production of the aromatic hydrocarbons especially benzene and toluene, I usually operate without water and at higher temperature, that is from 500° C. to 650° C.

20 Having thus described my invention, I claim as new and desire to secure by Letters Patent:

1. The method of cracking and distilling hydrocarbon oils, which consists in simultaneously subjecting the hydrocarbon oil under pressure, to heat, and to the attrition action of moving heat conducting metallic balls, in the presence of catalytic agents.

2. The method of cracking and distilling hydrocarbons which consists in subjecting the hydrocarbon under pressure to conducted, convected and radiated heat and at the same time to an attrition action by heated moving metallic mediums within an exteriorly heated revoluble retort, whereby the 35 gases and vapors produced are uniformly heated.

3. The method of cracking and distilling hydrocarbons which consists in subjecting the hydrocarbon under pressure to conducted, convected and radiated heat and at the same time to an attrition action, by means of metallic catalytic agents, whereby the gas or vapor produced is uniformly heated, 45 and then condensing the resultant gas or vapor.

4. The method of cracking and distilling hydrocarbon oils under pressure, by subjecting the same to the action of an exteriorly heated revolving retort charged with metallic balls and containing catalytic agents.

5. An apparatus for cracking and distilling hydrocarbons, comprising an exteriorly heated revoluble retort, heat-conducting and catalytic mediums in the form of metallic balls loose within the said retort and in rubbing contact with each other and the interior surface of the retort to conduct the heat from the periphery of the retort to the 60 interior thereof, to uniformly heat the contents, means for conducting the hydrocarbon under pressure into one end of the said retort, means for carrying off the resultant gases and vapors from the other end of the 65 retort, and means whereby the escape of the

heat conducting and catalytic mediums is prevented.

6. An apparatus for cracking and distilling hydrocarbons, comprising a furnace, a revoluble retort exteriorly heated and to 70 which the hydrocarbon under pressure is admitted and from which the reacting vapors are conducted, catalytic agents including metallic balls held in the said retort, and in rubbing and rolling contact with each other 75 and with the interior surface of the retort, the said balls acting as heat conductors to heat the contents of the retort to a uniform temperature, the balls conducting the heat quickly from the periphery of the retort to 80 the interior thereof, and by the rolling action maintaining fresh and active catalytic surfaces, thus promoting desirable chemical decompositions and recombinations.

7. An apparatus for cracking and distilling hydrocarbons, comprising a furnace, a revoluble retort in said furnace exteriorly heated, and to which the hydrocarbon under pressure is admitted and from which the vapors are conducted, catalytic agents including metallic balls held loose in the said 90 retort and acting as heat conductors and promoters of desirable chemical decompositions and recombinations, the balls being in rubbing and rolling contact with each other 95 and with the interior surface of the retort, the balls conducting the heat quickly from the periphery of the retort to the interior thereof, whereby the contents of the retort are heated to a uniform temperature and 100 overheating and undesirable decompositions are prevented.

8. An apparatus for cracking and distilling hydrocarbons, comprising a furnace, a retort within the said furnace and having 105 heads provided with hollow trunnions, bearings attached to the ends of the furnaces in which the said trunnions are journaled, the said trunnions being provided with apertures, driving means for rotating the said 110 retort, a combined hydrocarbon and steam or water supplying means connected with the bearing of one of the hollow trunnions and in register with the apertures in the trunnion for charging the retort with the 115 hydrocarbon to be cracked and distilled, and an outlet connected with the bearing of the other trunnion and registering with the apertures in the trunnion for carrying off the resultant gases and vapors, the outer ends 120 of the trunnions being closed, and the heads of the retorts being provided with apertures opening into the inner ends of the trunnions.

9. An apparatus for cracking and distilling hydrocarbons, comprising a furnace, a 125 retort within the said furnace and having heads provided with hollow trunnions the heads having small apertures at their central portions opening into said trunnions, driving means connected with one of the trun- 130

nions for rotating the said retort, a supplying means connected with one of the hollow trunnions for charging the retort with the hydrocarbon to be cracked and distilled, means connected with the said hydrocarbon supplying means for admitting steam or water to the retort, an outlet connected with the other trunnion for carrying off the resultant gases and vapors, and metallic balls held loose in the said retort and in rubbing and rolling contact with each other and with the interior surface of the retort.

10. An apparatus for cracking and distilling hydrocarbons, comprising a furnace, a retort within the said furnace and provided with hollow trunnions, bearings attached to the ends of the furnace and in which the said trunnions are journaled, driving means for rotating the said retort, a hydrocarbon supplying means connected with the bearing of one of the hollow trunnions and communicating with the interior of the trunnion, an outlet connected with the bearing of the other trunnion and communicating with the interior of the trunnion for carrying off the resultant gases and vapors, a water supply pipe connected with the hydrocarbon supplying means near the outlet end thereof, metallic balls held loose in the said retort and in rubbing and rolling contact with each other and with the interior surface of the retort, a drain cock on the said retort, and a manhole on the said retort, the heads of the said retort having small aperture opening into the trunnions.

11. The process of preparing lighter hydrocarbon oils from heavier oils, which comprises subjecting the vapors of heavier oils, under super-atmospheric pressure, as a progressively-advancing current to the action of

heat in a tubular zone containing metallic heat-transmitting bodies moving substantially transversely to the direction of flow of the vapor current and having a rubbing action, whereby carbon is prevented from adhering to the heating surface.

12. The process of preparing lighter hydrocarbon oils from heavier oils which comprises subjecting the vapors of heavier oils, under a super-atmospheric pressure, as a progressively advancing current to the action of heat, in a cracking zone containing metallic bodies moving substantially transversely to the direction of flow of the vapor current and having a rubbing action, whereby carbon is prevented from adhering to the heating surfaces.

13. The process of preparing lighter hydrocarbon oils from heavier oils which comprises subjecting the vapors of heavier oils, under a super-atmospheric pressure, as a progressively advancing current to the action of heat, in a tubular zone containing iron masses moving substantially transversely to the direction of flow of the vapor current and having a rubbing action, whereby carbon is prevented from adhering to the heating surfaces.

14. The process of preparing lighter hydrocarbon oils from heavier oils which comprises subjecting the vapors of heavier oils, under a super-atmospheric pressure, as a progressively advancing current to the action of heat, in a cracking zone containing iron masses moving substantially transversely to the direction of flow of the vapor current and having a rubbing action, whereby carbon is prevented from adhering to the heating surfaces.

ALFRED COCHRAN.
